UNITED STATES PATENT OFFICE.

JAMES ARAD ERWIN, OF OAK PARK, ILLINOIS.

HUMIDIFYING APPARATUS.

Application filed January 21, 1924. Serial No. 687,645.

The present invention relates to humidifying apparatus and particularly to humidifying apparatus adapted to be used in connection with buildings, such as schools, public buildings, theaters, dwelling houses, etc.

While many types of humidifying appliances or apparatus have been heretofore designed or suggested, it has been found that for one reason or another such appliances have never come into popular use. While it is universally recognized that it greatly promotes the comfort and well being of mankind to live in an atmosphere having a certain degree of humidity, and while prior inventors have endeavored to provide satisfactory humidifying appliances, yet nevertheless the only form of humidifying device used to any extent consists in the metal receptacle or tank adapted to be suspended upon a radiator and to contain water, which is heated by the radiator so that evaporation takes place. These evaporating tanks, are beneficial and serve to impart some degree of humidity to the atmosphere of the room in which they are placed, but they fall far short, however, of providing means whereby the theoretically correct conditions of moisture content of the air can be produced.

The object of my invention is to provide an automatic appliance, having a number of novel and important features, for maintaining at all times the atmosphere of a room at a certain degree of humidity, which degree of humidity may be selected by the occupant of the room. The water vapor is generated by novel means which may assume various forms. In one form of the invention, a portion of the heat which is normally wasted or discharged into the atmosphere by the waste products of combustion of a furnace, is utilized to generate steam which is discharged into the space to be humidified. Again, a gas fired or electrically heated appliance is used for creating water vapor, when it is desired to maintain the humidity of the atmosphere when there is no furnace fire, or where it is not desired to use the furnace gases to generate steam, such appliances are particularly useful. The invention is susceptible of considerable modification and may be embodied in various forms, the several embodiments illustrated in the accompanying drawings being set forth by way of example only.

In the drawings:

Figure 1 is a vertical section through a dwelling house having the usual steam or hot water boiler or furnace in the basement, showing one form of my humidifying apparatus installed therein;

Figure 2 is a longitudinal section through a steam generating device adapted to be placed in the conduit leading from the boiler or furnace to the chimney of a house heating plant to generate steam, utilizing the heat of the waste gases of combustion; and

Figure 3 is a section on line 3-3 of Figure 2;

In Figure 1, which is a section through a dwelling house, four rooms are illustrated, a chimney 10, a steam or hot water boiler or furnace 11 in the cellar, and steam or hot water radiators at 12 in the several rooms respectively. A horizontal flue or pipe 13 connects the top of the boiler 11 to the bottom of the flue 10, this pipe being preferably of sheet metal and being of ordinary construction, except in that a section is shown to be removed and a cylindrical casing 14 of larger diameter inserted in its place. Casing 14 is shown in Figure 2 upon a larger scale, and it will be seen that it consists essentially of a cylindrical central portion 15 and frusto-conical end portions 16, 16 which engage the adjacent ends of the flue 13. The gases of combustion from the furnace flow freely through this enlarged portion of the conduit. Supported concentrically within the cylinder 15 is a second cylindrical member 17 which consists in two coaxial cylindrical walls and two annular end plates, which enclose between them a water space 18 annular in vertical transverse section. Member 17 constitutes essentially a steam generator. It is provided with a downwardly projecting tubular portion 19 closed at its bottom by a screw cap 20 which may be removed for drainage purposes, and is also provided with an upwardly extending cylindrical portion 21 which constitutes a steam dome for collecting the steam generated. The downward extension 19 is connected to the steam dome 21 by means of two copper tubes 23 of the tortuous shape clearly shown in Figures 2 and 3, and the upper ends of these tubes may be below the water line in member 17, to decrease noise and facilitate circulation.

Positioned adjacent the cylinder 15 is a small tank 24, the upper portion of which is connected to the steam dome by a horizontal conduit 25, and the lower portion of which is connected to the tubular member 19 by a water tube or conduit 26. Normally water stands in the tank 24 to the height indicated in Figure 3, and hence water stands at the same level in the cylindrical 10 boiler member 17 and pipes 23, which are in free communication with the tank 24. A conduit 27 serves to conduct water from the city mains or a suitable source of supply to the tank 24, the flow of water into the tank 15 being controlled by a valve 28 to which is operatively connected a float 29. The construction is such that the water level is continuously maintained at the desired height 20 by the automatic operation of the float controlled valve.

From the top of tank 24 a steam pipe 30 leads upwardly, and through this steam pipe the steam intended to be discharged into the rooms above is conducted. As 25 shown in Figure 1, the pipe 30 communicates with a header, or horizontal distributing pipe 31 from which the vertical branch pipes 32 lead, these branch pipes terminating respectively in adjustable nozzles 33 in the respective rooms, through 30 which nozzles the steam is discharged into the atmosphere. Preferably these nozzles are placed as illustrated, when the rooms are heated by hot water or steam radiators, so 35 that the steam is carried upwardly by the heat rising from the radiators and, mingling with the air currents caused by the rising heat will be carried around the room, as indicated by the arrows in Figure 1. 40 Leading laterally from pipe 30 is a branch 35 which terminates at a point 36 within the conduit or flue 13. This branch is normally closed, however, by a safety valve indicated at 37 and flow of steam therethrough 45 only occurs when the pressure in the humidifying appliance has become unduly high. A pressure gauge is indicated at 38. Flow of steam into header 31 is also controlled by a valve 39 adapted to be operated 50 by a solenoid 40 which is in circuit with a transformer or battery 41 and a hygrostat 42. The hygrostat is positioned in one of 55 the rooms whose humidity it is sought to regulate, and is designed and constructed to cause the opening of valve 39 when the humidity falls below a predetermined point and the closing of the valve when the humidity reaches the desired degree.

In certain instances, fresh air ducts leading 60 from the outer atmosphere to the interior of a building are provided, such as indicated at 50 in Figure 1. The fresh air is introduced into the room above through a register 51 in the floor, and a steam nozzle 65 52 is provided for introducing steam into

the air flowing through conduit 50 and also to cause motion of air into the room through duct 50. The nozzle 52 is connected to the header 31 for this purpose.

Various forms of steam generators may 70 be employed, the selection of any particular one of which depending upon the conditions present in any locality and the preferences of the owner. The system of piping through the house may be used, if desired, 75 to convey disinfectants or perfumes or other vapors to the various rooms.

It will be obvious to one skilled in the art that still other forms of the invention may be devised, and it is not limited to the exact 80 design and arrangement of parts disclosed in those forms, which have been set forth by way of example.

Having thus described the invention what is claimed as new and desired to be secured 85 by Letters Patent is:

1. A humidifying apparatus including in combination, a heating plant having a flue for waste products of combustion, a steam or vapor generating tank, a conduit for conducting steam from said tank to a space to be humidified, and means for automatically delivering steam from said tank into said waste products flue when the pressure in said tank exceeds a pre-determined amount. 90

2. A humidifying apparatus including in combination, a steam or vapor generating tank, means for heating said tank, a conduit for conducting steam from said tank to a space to be humidified, a cut-off valve 10 in said conduit for interrupting the flow of steam therethrough, and means for preventing the pressure of the steam in the tank from exceeding a pre-determined amount when said cut-off valve is closed. 10

3. A humidifying apparatus including in combination, a heating plant having a flue for products of combustion, a steam or vapor generating tank, a conduit for conducting steam from said tank to a space to be 11 humidified, a regulating valve in said conduit, and means for discharging steam from said tank into said waste products flue when the pressure of the steam in said tank exceeds a pre-determined amount due to the 11 entire or partial closure of said regulating valve.

4. A humidifying apparatus including in combination, a steam or vapor generating tank, means for heating said tank, a conduit 12 for conducting steam from said tank to a space to be humidified, a regulating valve in said conduit, electro-mechanical means for operating the regulating valve in accordance with the relative humidity of the 12 space to be humidified, and means for preventing the pressure of the steam in the tank from exceeding a predetermined amount due to the operation of said regulating valve. 13

5. Apparatus for humidifying a space heated by means of radiators comprising, a steam or vapor generating tank and a conduit leading from said tank and having a discharge orifice in said space adjacent a heating radiator, the arrangement being such that the steam or vapor discharged in to said space is conducted therethrough by the convection currents of air created by said radiator. 10
- In testimony whereof I hereunto affix my signature.

JAMES ARAD ERWIN.
